Primary Examiner — David Muller*Assistant Examiner* — Nathan Johnston(74) *Attorney, Agent, or Firm* — Cantor Colburn LLP(57) **CLAIM**

I claim, the ornamental design for a dispenser, as shown and described.

DESCRIPTION

FIG. 1 is a perspective view of dispenser, showing my new design;

FIG. 2 is another perspective view thereof;

FIG. 3 is a left side elevation view thereof;

FIG. 4 is a right side elevation view thereof;

FIG. 5 is a front elevation view thereof;

FIG. 6 is a top plan view thereof;

FIG. 7 is another perspective view thereof;

FIG. 8 is another front elevation view thereof;

FIG. 9 is a perspective view thereof showing the dispenser in an open position; and,

FIG. 10 is a front elevation view thereof.

The broken lines shown in the drawings form no part of the claimed design.
